MAURITS J. SANDIN, OF WILKINSBURG, PENNSYLVANIA, ASSIGNOR TO WESTINGHOUSE ELECTRIC & MANUFACTURING COMPANY, A CORPORATION OF PENNSYLVANIA.

SWITCH MECHANISM.

Application filed August 22, 1922. Serial No. 583,607.

My invention relates to switch mechanisms and particularly to those provided with means for automatically operating them under predetermined conditions.

5 One object of my invention is the provision, in a rotatable snap switch, of means for either manually or automatically effecting the operation thereof.

Another object of my invention is the 10 provision of means, controlled by circuit conditions, for effecting an automatic operation of a rotatable snap switch and for automatically effecting a resetting of the automatic mechanism after each actuation 15 thereof.

Still another object is to simplify the construction of snap switches generally and to provide an improved form of operating mechanism therefor.

20 A further object of my invention is the provision, in a rotatable snap switch, of means whereby a single tension device may be employed to effect a snap movement thereof upon either manual or automatic 25 operation.

It has been heretofore proposed to employ fusible members that are controlled by current in the circuit for permitting the switch to open upon the occurrence of an 30 overload, but none of the prior art of which I am aware has proposed to employ such a device in connection with a fully rotatable switch wherein a single tension device is employed.

35 As shown in the accompanying drawings, Figure 1 is a view, partially in side elevation and partially in section, of a switch embodying my invention.

Fig. 2 is a view thereof partially in plan and partially in section,

Fig. 3 is a bottom plan view thereof,

Fig. 4 is a sectional plan view of certain of the switch parts shown in the positions occupied thereby when the circuit through 45 the switch is completed,

Fig. 5 is a similar view showing the position occupied by the said parts when the circuit through the switch is broken,

Fig. 6 is a sectional view of the thermal 50 device which I employ, and

Fig. 7 is a detail view of one of the locking members.

I provide a base 7 to the outer side of which are secured stationary contact mem-

bers 8 and 9 that carry terminals 10 and 11, 55 respectively.

A turn button 12 is secured to one end of a shaft 13 that extends through the base. A ratchet wheel 15 is secured to the other end of the shaft 13. A bearing block 16 for 60 the shaft 13 is set into a recess in the outer side of the base 7 to relieve the base of wear through the turning of the shaft.

A gear wheel 18 lies against the base 7 and is loosely supported by the shaft 13. A 65 camming disc 20 (Figs. 4 and 5) is rigidly secured to the shaft 13 and abuts against the outer side of the gear wheel 18.

A blade carrier 22 is loosely supported upon the shaft 13, for supporting a blade 70 or bridging member 23, being insulated therefrom by washers 25. A spring 26 engages the carrier 22 and a collar 27 that is secured to the shaft 13.

The blade carrier, at its inner side, has a 75 lock plate 28 secured thereto by rivets 29 (Fig. 7). The plate 28 is provided with a slot 30 in which slides an outwardly extending lug 31 of a camming ring 32 that surrounds the cam disc 20. The ring 32 is 80 also provided with a radially extending portion 34 that serves as a stop member, as will be hereinafter described.

The spring 26 is normally under tension and the shaft 13 is held against counter-clockwise movement by means of the ratchet wheel 15 and the spring-pressed pawl 15a 85 (Fig. 3).

The blade carrier 22 is biased, through the tension of the spring 26, in a clockwise 90 direction. Movement thereof, however, is prevented by reason of the stop member 34 abutting against one of the stops 36, 37, 38 and 39 that project outwardly from the gear wheel 18. The slot 30 in the plate 28 holds 95 the ring 32 against rotative movement relatively to the blade carrier 22.

The gear wheel 18 is prevented from turning, by a gear wheel 41 that is secured to a 100 shaft 42 by fusible material, or solder, 43 (Fig. 6). The shaft 42 is cemented in a cylindrical member 44 and thereby held against turning. It will thus be seen that, so long as the solder 43 holds, the blade carrier 22, and the blade 23 that is carried thereby, cannot move, unless the camming ring 32 is so moved as to carry the stop member 34 out of engagement with the stop 105.

members 36, 37, 38, 39, carried by the gear wheel 18.

In order to advance the switch to open position, the button 12 is turned in a clockwise direction, thus increasing the tension of the spring and rotating the camming plate 20, to move the cam ring 32 to the right (Fig. 4). This movement withdraws the lug 31 from engagement with the stop member 37 and permits the blade carrier to be advanced by the spring 26. As the carrier advances, it carries with it the camming ring 32, by reason of the engagement of the lug 31 thereof with the walls of the slot 30 in plate 28. This movement of the cam ring rotates it about the cam plate 20 that has just been given rotative movement through 90° arc, as above explained, until it has reached substantially its former position relatively to the cam plate 20, at which time the stop 34 thereof will make engagement with the stop 38 of the gear wheel 18. The bridging member 23 then occupies its open position. Further turning of the button 12 will advance the camming ring into engagement with the stop members 39, 36 and 37, successively.

To effect an automatic actuation of the switch, to break the circuit, when the parts are in the position shown in Figs. 1 and 4, it is necessary to release the gear wheel 18 and permit it to rotate under the action of the spring 26.

A resistance wire or heating element 46 is imbedded in the cement contained in the cylinder 44 and is connected in series with the circuit through the switch. The resistance element 46 is an extension of the lead 47 and current flows therefrom, through the shaft 42, a terminal plate 48 (Fig. 2), shunt 49, terminal 11, contact member 9, bridging member 23, and contact member 8 to the terminal 10.

Should the current in the circuit exceed a predetermined value, the heating element 46 will cause the solder 43 to soften, thus permitting the gear wheel 41 to rotate on the shaft 42, and releasing the gear wheel 18. The tension normally exerted by the spring 26 may now move the carrier 22, and the gear wheel 18 in a clockwise direction.

The shaft 13 and the cam plate 20 carried thereby do not move, as they are biased in a counter clockwise direction, against the pawl 15a, by the spring 26. Therefore, the camming ring 32, by reason of its engagement with the slot 30 of the plate 28, is rotated around the cam disc 20 until the extension 34 thereof is in substantially radial alignment with the shaft 13. At this period, the lug 31 is at the limit of its radial path of movement, and moves into engagement with a raised stop member 50 (Fig. 5) that is secured to the base 7, thus bringing the switch parts to rest at open position.

The solder will then become cooled and the gear wheel 41 again locks the gear wheel 18 against movement. The switch is now ready for another manual operation, by means of the button 12, whereby the lug 31 of the cam ring 32 is withdrawn from the stop member 50 and the extension 34 withdrawn from the stop 38 of the gear wheel 18. The tension of the spring 26 is meanwhile being increased and the parts are snapped into a position wherein the cam ring extension 34 abuts against the lug 39, as heretofore described. The switch is now closed and ready for either an automatic or a manual opening operation. A further automatic operation will carry the lug 31 into engagement with the raised stop member 51 disposed diametrically opposite the member 50 (Figs. 1 and 3). This automatic movement is essentially the same as the other automatic movement above described.

The lug 31 is never entirely out of engagement with the walls of the slot 30, and, at each of the two automatically released positions of the switch, is in engagement both with one of the stops 50 and 51 and with the slot 30. The blade carrier 22 can never move without imparting rotative movement to the camming ring 32 and, owing to the interengagement of the ring and the cam plate 20, all movements of the ring are combined rotative and reciprocatory motions.

From the foregoing it will be seen that I provide a switch that may be automatically moved to open position and that is automatically reset for further automatic operation. Also one wherein the manual operation of the switch may be freely effected without affecting the automatic mechanism and sufficient tension stored, when closing the switch, to insure a snap movement thereof to open position when automatically released.

Various changes in detail and general arrangement may be made without departing from the spirit and scope of the invention as defined by the accompanying claims.

I claim as my invention:

1. The combination with a progressively rotatable switch member, of an actuating spring therefor, manually-operable means for placing the spring under tension to cause a snap movement of the said member, means for retarding the movement of the switch member, means responsive to the current in the circuit whenever the circuit is closed by the switch member for controlling the retarding means, and means whereby the energy stored in the spring during manual operation of the switch member to one position causes movement of the said member to another position when the retarding means is actuated.

2. The combination with a rotatable snap switch and a tension device for actuating the

same, of a normally stationary stop member for retarding the movement of the switch, a stop member manually movable out of engagement with the first named stop member 5 to permit movement of the switch, a thermally-controlled member for permitting movement of the first named stop member, under predetermined conditions and a permanent stop member for arresting the last 10 named movement at a predetermined point.

3. The combination with a rotatable switch member and a tension member therefor, of means for storing energy in said tension member, a carrier for said member, a 15 stop member supported on the carrier, a gear wheel provided with stop members in position to be engaged by the first named stop member at predetermined positions of the said switch member, a second gear wheel, 20 meshing with the first named gear wheel, and means responsive to conditions in the circuit for permitting the gear wheels to rotate.

4. The combination with a rotatable 25 switch member and a tension member therefor, means for storing energy in said tension member, a carrier for said member, a stop member supported on the carrier, a gear wheel provided with stop members in position to be engaged by the first named stop member at predetermined positions of the said switch member, a second gear wheel meshing with the first named gear wheel, 30 a fusible member for normally maintaining the second gear wheel against movement, and a heating element in series with the switch for softening the fusible element to permit movement of the gear wheels.

5. The combination with a rotatable 40 switch member and a tension member therefor, means for storing energy in said tension member, a carrier for said member, a stop member supported on the carrier, a gear wheel provided with stop members in position to be engaged by the first named stop member at predetermined positions of the said switch member, a second gear wheel meshing with the first named gear wheel, 45 means responsive to conditions in the circuit for permitting the gear wheels to rotate, and means limiting the movement of the said gear wheels after they have been released.

6. The combination with a rotatable switch member of a tension member therefor, means for storing energy in the tension member, a shaft for the rotatable member, a cam member supported by the shaft and having a locking lug thereon, a movable member provided with stop members for engaging the said locking lug, a fusible member for normally holding the movable member against movement, means controlled by conditions in the circuit for rendering the fusible member ineffective to hold the said 60 movable member in fixed position, and means

for limiting the movement of the said movable member whenever it has been released by the fusible member.

7. In a rotatable snap switch, a progressively rotatable blade member, contact members co-operating therewith, an actuating spring for the blade member, manually operable means for placing the spring under tension to cause a snap movement of the blade member, means for retarding the 75 movement of the blade member, means at all times responsive to the current traversing the switch for controlling the retarding means, and means whereby the energy stored in the spring during manual operation of 80 the switch causes movement of the blade member to another position when the retarding means is actuated.

8. In a rotatable snap switch, a progressively rotatable blade member, contact members co-operating therewith, an actuating spring for the blade member, manually operable means for placing the spring under tension to cause a snap movement of the blade member, means for retarding the 85 movement of the blade member, means at all times responsive to the thermal action of the current traversing the switch for controlling the retarding means, and means whereby the energy stored in the spring during manual operation of 90 the switch causes movement of the blade member to another position when the retarding means is actuated.

9. Switch mechanism comprising a contact member, a switch member movable into engagement with the contact member, means including a progressively rotatable shaft for operating the switch, and means manually operable to retaining position for releasably 100 releasing the switch in engagement with the contact member, the said means being current responsive for releasing the said switch member.

10. The combination with a rotatable snap 110 switch and a tension device for actuating the same, of a normally stationary stop member for retarding the movement of the switch, a stop member manually movable out of engagement with the first named 115 stop member to permit movement of the switch, a thermally-controlled member for permitting movement of the first named stop member under predetermined conditions and a permanent stop member for arresting 120 movement of the switch at a predetermined point.

11. The combination with a rotatable snap switch and a tension device for actuating the same, of a normally stationary stop 125 member for retarding the movement of the switch, a stop member manually movable out of engagement with the first named stop member to permit movement of the switch, a current responsive member for permit- 130

- ting movement of the first named stop member under predetermined conditions and a permanent stop member for arresting movement of the switch at a predetermined point.
- 5 12. The combination with a rotatable snap switch and a tension device for actuating the same, of a pair of relatively movable stop members for successively retarding the movement of the switch, a stop device for
10 the switch manually movable out of engagement with the said stop members to permit movement of the switch, and a current responsive device for permitting relative movement of the first said stop members to
15 release the said stop device.
13. The combination with a snap switch and a tension device for actuating it, of a pair of cooperating movable stop members for releasably retarding movement of the switch, one of the said members being manually operable to releasing position with respect to the other to permit movement of the switch and the other of the said members being current responsive and movable to releasing position with respect to the 25 other to permit movement of the switch.

In testimony whereof, I have hereunto subscribed my name this 10th day of August 1922.

MAURITS J. SANDIN.
